CARTON.

Filed Jan. 23, 1923

UNITED STATES PATENT OFFICE

GEORGE H. BENT, OF BATTLE CREEK, MICHIGAN

CARTON

Application filed January 23, 1923. Serial No. 614,422.

This invention relates to cartons and particularly to cartons provided with an inner lining.

It is desirable, when packaging a large variety of oily materials such as cloves, cinnamon, spices and the like, and when packaging candies, confections, etc., to provide the carton with an inner lining such as a cellulose parchment liner, or one formed of some suitable non-absorbent material. This lining prevents the oil from striking through or impregnating the carton walls and rendering the package unsightly and unsaleable. It also prevents sugar-coated products from sticking and adhering to the inner walls of the carton.

Because of the large quantities of inner-lined cartons required by present-day markets, machinery has been devised for forming the lined cartons and filling the same with the desired contents. This last operation, however, presents a difficulty that has not, heretofore, been successfully overcome since the parchment liner, due to its thin flexible walls, will not readily conform and remain in contact throughout its extent with the inner walls of the carton while empty and during the filling operation.

In the interval in which the lined carton is being conveyed from the carton-making machine, as by endless belt or chain, to the point where the material is automatically fed by suitable mechanical means into the same, the walls of the liner are frequently flexed or warped away from the walls of the surrounding carton, with the result that a portion of the materials is deposited or filled in the spaces thus afforded between the liner and the carton. Also, in many instances, this warping of the liner walls occurs during the filling operation and after a small portion of the contents has been directed into the lined carton, since it is impossible to initially distribute the materials in equal quantities over the entire bottom of the liner. A tendency to distort the shape of the liner is thereby set up which results in an inward bulging of the walls of the same, and the contents are partly discharged into the spaces thus formed between the lateral walls of the liner

and the carton. Consequently, the advantages to be obtained by the use of a liner are destroyed and frequently the volume of the container is materially decreased.

It has been proposed to paste the liner to the carton blank entirely along the length thereof so that the two elements may be simultaneously folded into box-like form, to overcome the highly undesirable effects resulting from warped or inwardly bulging walls. When this is not done, the disadvantages set forth have been experienced unless the lined cartons were filled manually, or so slowly as to insure the reception of the entire charge within the liner, which, in either case, results in a loss of time, or in increased expense, or both.

An object of this invention is to provide, as an article of manufacture, a simple, inexpensive, lined carton such that the walls of the liner will not warp or become distorted either prior to or during the filling operation, and one which may be machine-filled, if desired, without necessitating the use of a funnel; and this is effected by applying a small horizontal strip, or strips, of adhesive to the liner or carton adjacent the line of fold of the top flaps prior to the association of the liner with the carton, in such a manner that the liner will be securely held, when installed, in contact with the inner walls of the carton during the filling operation.

The invention will be more readily understood by reference to the accompanying drawings, in which:—

Fig. 1 is a view, in perspective, illustrating one embodiment of the present invention;

Fig. 2 is a sectional side elevation, on an enlarged scale, of the carton shown in Fig. 1;

Fig. 3 is a view, in perspective, illustrating the carton and liner before the latter has been completely associated with the carton;

Fig. 4 is a sectional view, on a reduced scale, taken on line 5—5 of Fig. 2;

Fig. 5 is a view similar to Fig. 4 illustrating the adhesive material applied to the carton rather than the liner; and

Fig. 6 is a view similar to Figs. 4 and 5 showing the manner in which walls of the

ordinary liner warp or bulge inwardly prior to and during the filling operation.

Referring to the accompanying drawings, wherein like reference numerals indicate like parts, 1 is a carton, preferably formed by suitable machinery from a single blank into any desired shape and size, provided with scoring lines 2, 3, 4, etc., cutting lines 5, and flaps 6 and 7.

10 A liner 8, formed in any desired manner from a suitably shaped blank of cellulose parchment or other suitable material, is employed as the inner member of my improved carton. The size of the liner blank is substantially the same as the size of the carton blank in order to provide foldable portions at opposite extremities of the liner, and said foldable portions of the liner are entirely free with respect to the foldable portions or flaps of the carton (Figs. 1 and 2), in order to facilitate sealing of the package after the same has been filled. Preferably, I apply a narrow strip 9, of glue or paste, to each of side walls 10 of liner 8 in such a position that, 25 when the liner is completely associated with carton 1, strips 9 will be closely adjacent, but below, and substantially parallel to the upper end of side walls of carton 1 or scoring lines 3. Since the liner in a carton always engages 30 the carton tightly adjacent the fold lines of its sides, it is not essential in overcoming bulging of the liner to extend strips 9 the full width of the side walls 10 of the liner. As shown in Fig. 1, strips 9 terminate at both 35 ends within the area defined by scoring lines 3 and 4 and in this manner a great saving of adhesive is effected. If desired, strips 9 may be applied in any suitable manner to the inner side walls of the carton in the same relative 40 position, i. e. adjacent to, but slightly below, and substantially parallel to scoring lines 3, as indicated in Fig. 5.

When my improved carton is formed and assembled by machinery now in use and particularly adapted for such work, the cartons and liners are formed and one end thereof closed and sealed after the assembly of the two members. Adhesive strips 9 are applied to the liner 8 or the carton before the two are 45 associated. Any suitable means may then be employed to insure that the glue or paste strips shall cause the liner to adhere to the walls of the carton or, if desired, the two parts may be manually forced together adjacent said strips. Figs. 1 and 2 illustrate the 50 results of this assembly.

When my improved carton is being conveyed to the filling point and during the filling operation, liner 8 is held in close contact with the inner walls of carton 1 as indicated in Fig. 4 with the result that it is impossible for small particles of the material being packaged to fall or enter between the respective walls of the two members forming the 55

70 container. I thereby prevent the warping or inward bulging of the walls of the liner, as illustrated in Fig. 6, and thus obviate in a cheap, simple and effective manner the great disadvantages and objections that are heretofore stated.

75 The cartons normally in use are of such size that it is ordinarily unnecessary to apply the adhesive strips 9 in any other manner than described and illustrated.

80 However, in unusually large cartons, it may be desirable to extend the strip of adhesive around the four sides of the carton to insure against the formation of the objectionable 85 spaces 11.

85 The invention is capable of receiving a variety of expressions, one of which is illustrated in the accompanying drawings, but it is to be expressly understood that the drawings are for purposes of illustration only and are not designed as a definition of the limits of the invention, reference being had for this purpose to the appended claim.

90 What is claimed is:—

95 A carton comprising an outer member of cardboard or the like provided at the upper end thereof with package-closing portions extending from four side panels of said member, and a separately formed, flexible paper liner adapted to be assembled therewith and having restricted adhesive areas adapted to attach it to the outer member on two opposed top portions only of said member and having a body portion in the outer member substantially free of the walls thereof, said liner having a package-closing portion adjacent to and entirely free from the package-closing portions on the outer member and adapted for independently reclosing when portions of the 100 contents have been removed.

105 In testimony whereof I have signed this specification.
